Primary Examiner — Stella Reid*Assistant Examiner* — Janice Lim(74) *Attorney, Agent, or Firm* — Nina Habib Borders; Reed Smith LLP(57) **CLAIM**

The ornamental design for an insole bottom, as shown and described.

DESCRIPTION

FIG. 1 is a top perspective view of an insole bottom, showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines showing the remainder of the footwear insole show unclaimed subject matter only and form no part of the claimed design.
